UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

ROTARY PRINTING-PRESS.

1,090,013.

Specification of Letters Patent. Patented Mar. 10, 1914.

Application filed May 18, 1910. Serial No. 562,335.

To all whom it may concern:

Be it known that I, HENRY F. BECHMAN, of Battle Creek, in the county of Calhoun and State of Michigan, have invented certain new and useful Improvements in Rotary Printing-Presses; and I hereby declare that the following is a full, clear, and exact description thereof, reference being had to the accompanying drawings, which form 10 part of this specification.

This invention is an improvement in rotary printing presses of the general type shown in my Patent No. 867,230 of October 1, 1907 and my application No. 1373.

15 The object of the present invention is to produce a rotary press in which papers of any desired size, up to the page capacity of the press, may be produced with a less number of plates than there are pages to be 20 printed,—the press being adapted to produce two or more papers, of the same or different number of pages, at the same time. For instance, if the total page capacity of the press shown in Figures 1 and 2 of the 25 accompanying drawings should be 24 pages the press can produce simultaneously, for example, two 12-page papers; while the total number of plates required for producing 24 pages is but 18 in the press shown, in 30 which for printing a minimum sized paper of 12 pages nine plates are required.

A further object of the invention is to 35 make a compact rotary press in which all parts are easily accessible and to reduce the number of impression cylinders required, compared with the number of plate cylinders.

I will now describe the invention in detail 40 with reference to the accompanying drawings which conventionally illustrate one practical form of press embodying the invention, and will in connection with the following description impart a clear understanding thereof, and enable any one skilled in the art to construct and use the same; it 45 being understood however that the invention is not restricted to the particular size and construction of press shown in the drawings.

In the drawings—Fig. 1 is a diagrammatical sectional elevation of a rotary printing press embodying the present invention and adapted to simultaneously print six webs of paper. Fig. 2 is a diagrammatical

plan view of such press and folding mechanism therefor, when the plate-cylinders are 55 two pages long and print two-page-wide webs. Fig. 3 is a detail view of the folding mechanism for such a press, when the plate-cylinders are four pages long and print a four-page wide web,—or two two-page-wide 60 webs showing the lead of the webs for producing two 24-page papers simultaneously. Fig. 4 is a view similar to Fig. 3 showing the lead of the webs for producing four 12-page papers simultaneously. 65

The press as shown in Fig. 1 has two preferably vertically disposed series of printing mechanisms at the right and left hand ends thereof, which series are differently constructed; but each printing couple 70 in each series comprises a plate cylinder and a co-acting impression cylinder; and each web is led first between a printing couple in one series to be printed on one side, and then between a printing couple in the opposite series to be perfected, and is then directed to the folding mechanism which is preferably located at the side of the press beyond the ends of the cylinders. 75

Each plate cylinder in the machine as 80 shown in Fig. 1 is of small diameter as compared with the cylinders of the ordinary rotary presses, and is adapted to carry only single-page tubular-plates P such as shown and described in my patent aforesaid; each 85 of such plates substantially surrounding its plate cylinder, when placed thereon, except for the narrow space left between the ends of the type surface of the plate necessary to give the required margin between successive impressions on the web; and each plate will therefore be practically continually in impression and printing the web.

The right hand series of printing mechanisms comprises four impression cylinders 95 and three plate-cylinders, which are preferably arranged in a vertical tier. In such series the lowest impression cylinder 1 co-acts with a superposed plate cylinder 2; which also co-acts with a superposed impression cylinder 1^a; that also co-acts with a plate cylinder 2^a; which also co-acts with a superposed impression cylinder 1^b; that also co-acts with a superposed plate cylinder 2^b; which also co-acts with a superposed impression cylinder 1^c. Each plate cylinder 2, 100

^{2^a, 2^b}, is thus arranged and adapted to co-act simultaneously with two impression cylinders, and therefore to simultaneously produce two impressions upon different webs presented by the co-acting impression cylinders at each rotation thereof. The plates P on the plate cylinders 2, 2^a, 2^b are inked before each impression by means of two inking mechanisms 5 and 5^a arranged at opposite sides of each cylinder 2, 2^a, 2^b as indicated in the drawings; such inking mechanisms being of ordinary construction and well understood need no detailed explanation or illustration; but it will be obvious from the drawings that the plates on the cylinders 2, 2^a, 2^b, will be freshly inked before each impression, or twice during each rotation of the plate cylinders.

The left hand series of printing mechanisms, comprise three impression cylinders 3, 3^a, 3^b, and co-acting plate cylinders all of which are preferably arranged parallel in the same vertical plane. With the impression cylinder 3 co-act two plate-cylinders 4, 4^a, respectively above and below said impression cylinder; with the impression cylinder 3^a, co-act two similarly arranged plate-cylinders 4^b, 4^c; and with the impression cylinder 3^b co-act two similarly arranged plate-cylinders 4^d, 4^e. Each plate-cylinder 4, 4^a, 4^b, 4^c, 4^d, 4^e, in the arrangement shown prints on but one web, and consequently each of such cylinders is only provided with one inking mechanism indicated at 5^b, similar to the inking mechanisms 5, 5^a, of the other plate cylinders 2, 2^a, 2^b.

Each plate cylinder of the press as shown is adapted to carry one or more single-page-tubular plates, arranged end to end on such cylinder; and as indicated in Fig. 2, each plate cylinder can carry two of such single-page tubular-plates P arranged end to end thereon. A press having the number of plate cylinders shown in Fig. 1, each two pages wide, would have a total capacity of twenty-four pages, or two papers of twelve pages each, which could be produced from eighteen single-page plates, because each plate on the cylinders 2, 2^a, 2^b, simultaneously prints two webs, and thus performs practically twice as much work as each plate on the cylinders 4, 4^a, 4^b, 4^c, 4^d, 4^e.

The total capacity of this press can be varied by varying the length of the plate cylinders. For example by making the plate cylinders carry only a single plate, the total capacity of the press would be twelve pages produced from nine plates. If the plate cylinders are made two plates wide the total capacity of such press would be twenty-four pages produced from eighteen plates. If the plate cylinders are made three plates wide the total capacity of the press would be thirty-six pages produced from twenty-seven plates. If the plate-

cylinders are made four-plates wide, the total capacity of such press would be forty-eight pages produced from thirty-six plates. It will be obvious that by this invention a great saving in the number of plates is effected, and furthermore as each plate in the press is always printing there is no lost time, as compared with the ordinary rotary presses in which the plate cylinders carry two semi-circular plates around their circumference. Each plate on cylinders 4, 4^a, 4^b, 4^c, 4^d, 4^e, will print twice as many impressions in the same time, moving at the same peripheral speed, as the plates on the plate cylinders in the ordinary rotary presses. And each plate on the cylinders 2, 2^a, 2^b, simultaneously prints two webs, and therefore will print four times as many impressions, in the same time and moving at the same peripheral speed, as will a plate in the ordinary rotary printing presses. I thus obtain by this invention a much greater product—from a fewer number of plates—than can possibly be obtained in the ordinary rotary printing machines.

The press shown in Fig. 1 is adapted to simultaneously print six different webs each equal in width to the length of the number of plates on each plate cylinder when the press is operating at full capacity.

As shown in Figs. 1 and 2 the lowermost web w¹ is led from a roll W¹ at the left hand end of the press over guides 6 to and between plate cylinder 4 and impression cylinder 3 thence past guides 6^a to and between impression cylinder 1 and plate cylinder 2; thence past guide 6^b to the folding mechanism. The next web w² is led from a roll W² at the right hand end of the press, over guides 7 to and between plate cylinder 2 and impression cylinder 1^a and thence past guides 7^a to and between impression cylinder 3 and plate cylinder 4^a and thence past guide 7^b toward the folder. The third web w³ is led from roll W³ at the left hand end of the press over guides 6^c to and between cylinders 4^b, 3^a, thence past guides 6^d to and between cylinders 1^a, 2^a, and thence past guide 6^e to the folder. The fourth web w⁴ is led from a roll W⁴ at the right hand end of the machine over guides 7^c to and between cylinders 2^a, 1^b, thence past guides 7^d to and between cylinders 3^a, 4^c, and thence past guide 7^e to the folder. The fifth web w⁵ is led from a roll W⁵ at the left hand end of the machine over guides 6^f to and between cylinders 4^d, 3^b, thence past guides 6^g to and between cylinders 1^b, 2^b, thence past guide 6^h to the folder. A sixth web w⁶ is led from a roll W⁶ at the right hand end of the press over guides 7^f to and between cylinders 2^b, 1^c, and thence past guides 7^g to and between cylinders 3^b, 4^d, and thence past guide 7^h to the folder.

The webs w¹, w³, w⁵, run through the press

from left to right; while the webs w^2 , w^4 , w^6 , run through the press from right to left. The adjacent webs w' , w^2 ; w^3 , w^4 ; and w^5 , w^6 , respectively, contact with opposite sides 5 of the same plate cylinders at the right hand end of the press, and with opposite sides of the same impression cylinders at the left hand end of the press; and therefore the webs in each pair must move in opposite 10 directions.

The folding mechanisms might be arranged at the ends of the press as indicated in my patent, and in my application aforesaid; but I preferably locate the folders at 15 one side of the press.

As shown in Fig. 2 where two page wide webs are used two folders F , F' , may be located adjacent the ends of the press, and the web w' after passing guide 6^b is given 20 a quarter turn over an angle bar 8 , then led out and turned over a roller 9 , and then led back across the press to the folder F . Similarly each web w^3 and w^5 can be led over 25 similarly arranged angle bars 8 and turning rollers 9 and carried to the folder F , and assembled there with the web w' , as indicated in the drawings.

The web w^2 after passing guide 7^b could 30 be turned over an angle bar 8^a and led direct to the folder F' , as indicated in Fig. 2. Webs w^4 and w^6 can be turned over similar angle bars 8^a and led direct to the folder F' and assembled there with web w^2 . Any 35 suitable arrangement of angle bars and turning rollers may be employed at the ends of the press which will by giving a web a quarter turn enable it to be directed from the press to a folder at the side thereof.

40 Where the plate-cylinders are made more than two pages wide, more folders can be employed; and in Figs. 3 and 4 I have indicated an arrangement of folders for four-page wide webs.

45 As shown in Fig. 3 I provide two folders F^2 , F^3 , near the right hand end of the press to fold the webs w' , w^3 , w^5 ;—and I provide two folders F^4 , F^5 , near the left hand end of the press to fold the webs w^2 , w^4 , w^6 . Each of the four-page wide webs w' , w^3 , w^5 , after being printed may be turned over its 50 related angle bar 8 , then carried out and turned over the roller 9 , and each centrally divided by a slitter S . One half of each 55 divided web w' , w^3 , w^5 , is carried to the folder F^2 , and the other halves of such webs are carried to the folder F^3 . Similarly each of the webs w^2 , w^4 , w^6 , may be turned over their respective angle bars 8^a , and then slit 60 longitudinally by a slitter S' , and one-half of each web w^2 , w^4 , w^6 , then led to the folder F^4 , and the other halves of such webs (w^2, w^4, w^6) led to the folder F^5 . With this

65 arrangement of parts a press like that in Fig. 1 with four-page-wide plate cylinders

will print and deliver simultaneously four twelve-page papers or a total of forty-eight pages from thirty-six plates.

In Fig. 4 a similar arrangement of folding mechanisms is provided for four-page wide webs but an additional angle bar 8^c is employed adjacent each bar 8 , and a supplemental angle bar 8^d is employed adjacent each angle bar 8^a ; in this construction the four-page wide webs w' , w^3 , w^5 , 70 after being printed may be divided by any suitable means, as by slitters S^2 indicated in the drawings; and then one-half of each web is turned over its angle bar 8 and led over roller 9^b to folder F^2 , while the other half of each web is turned over angle bar 8^c and led over roller 9^c to folder F^3 . This arrangement gives a total of twenty-four pages assembled at one folder. By providing an additional angle bar 8^e , Fig. 4, adjacent each bar 8 , both halves of the four-page wide webs w' , w^3 , w^5 , could be assembled on the folder F^2 . Similarly webs w^2 , w^4 , w^6 , after being printed may be divided as by slitters S^3 indicated in Fig. 4, and one-half of each web can be led over its related turning bar 8^a to the folder F^4 , and the other half can be led over a supplemental angle bar 8^d to the folder F^5 . Thus producing a twenty-four page paper from the 90 webs w^2 , w^4 , w^6 , delivered at one folder. By providing an additional angle bar 8^f adjacent each angle bar 8^a (Fig. 4) both halves of the webs w^2 , w^4 , w^6 , can be assembled together at folder F^6 .

By the described, or equivalent arrangements, of angle bars and turning rollers it is obvious that several different sized papers can be printed and folded separately at the same time upon different folders; and the total capacity of the press indicated in Figs. 3 and 4 would be forty-eight pages printed from thirty-six plates; which would enable two twenty-four page papers to be produced simultaneously as indicated in Fig. 4, or twelve four-page papers to be produced simultaneously, as indicated in Fig. 3; and obviously by varying the number or width of the webs, or by varying the manner in which the halves of the webs are assembled at the folders, it is possible to simultaneously produce two, three or four papers of different number of pages, aggregating in pages up to a total of forty-eight pages, at each operation of the press.

The arrangement of angle bars and turning rollers can of course be varied to suit the constructor, and in accordance with the size of the press, and width of webs to be printed thereon. Having all the folders at 110 the side of the press enables the pressman to readily observe the condition of all the papers, and also shortens the total length of the machine. The press shown in Figs. 1, 3 and 4, using only thirty-six single-page 120

130

4 tubular plates can produce twelve-page papers at a rate of 100,000 per hour; twenty-four of the plates, *i. e.* those on cylinders 4, 4^a, 4^b, 4^c, 4^d, 4^e, printing only one web each; while each of the plates (12) on cylinders 2, 2^a, 2^b, prints two webs simultaneously. All of the plates on the cylinders print all the time when in operation; those on the left hand plate-cylinders each 10 making consecutive impressions on one web, and those on the right hand cylinders each simultaneously making two consecutive impressions on two webs.

15 The operation of the plates would be just the same as above described if the plate cylinders were only one page wide, but in such case the total capacity of the press shown in Fig. 1 would only be twelve pages. If the plate cylinders are made two pages wide 20 the press would have a total capacity of twenty-four pages and could deliver 50,000 twelve-page papers per hour using only eighteen single page plates; in which case fourteen of these plates would be making 25 single impressions all the time upon one web, while the remaining six plates would be making two impressions all the time upon two webs. Papers of any size, less the maximum, can be produced on such press by 30 using fewer plates and less webs; or narrower webs. The total capacity of the press could also be increased by adding additional plate and impression cylinders in the respective series. It can also be lessened, by reducing the number of plate and impression 35 cylinders in such series; and printing a less number of webs.

40 While I have shown the impression cylinders in the present instance as of about twice the diameter of the plate cylinders, this is merely a matter of preference, and the impression cylinders may be made of small diameter like the plate cylinders, if desired; which would reduce the height of 45 the press, but also lessen the space between the adjacent superposed sets of inking mechanisms.

Having described my invention I claim:

50 1. In a rotary printing press, the combination of a series of printing mechanisms comprising plate and impression cylinders, the plate-cylinders being adapted to carry single-page tubular plates extending around the circumference of the cylinder, and each 55 plate cylinder being arranged between and co-acting with two impression cylinders; and a second series of printing mechanisms comprising a plurality of impression cylinders and two plate cylinders carrying single- 60 page tubular plates co-acting with each impression cylinder; with means for directing pairs of webs successively between a plate cylinder and impression cylinders in one series to be printed on one side, and between an impression cylinder and plate-cylinders

in the other series to be perfected, and means for folding the webs.

2. In a rotary printing press, the combination of two adjacent series of printing mechanisms comprising alternate plate cylinders and impression cylinders, each plate cylinder in one series co-acting with two impression cylinders, and each impression cylinder in the other series co-acting with two plate cylinders, each plate cylinder being adapted to carry only single-page tubular plates; and means for directing a plurality of superposed webs successively between the printing couples in the adjacent series; with a plurality of folding mechanisms adjacent each end of the press, means for slitting the webs, and means for directing the halves of the slit webs to the same or different folding mechanisms.

70 3. In a rotary printing press, the combination of a series of plate cylinders and impression cylinders, each plate cylinder being adapted to carry single-page tubular plates substantially extending around the circumference of the cylinder, each plate cylinder being arranged between and co-acting with two impression cylinders, so that each page plate on each cylinder will simultaneously print two webs; and an adjacent series of plate cylinders and impression cylinders, each impression cylinder being arranged between and co-acting with two plate cylinders so as to simultaneously present two webs to the plates on said cylinders, and means for directing a plurality of webs 90 successively between printing couples in the adjacent series to be perfected; with a plurality of folding mechanisms adjacent each end of the press, and means for slitting the webs and means for directing the halves of the slit webs to the same or separate folding mechanisms.

95 4. In a rotary printing press, the combination of a printing mechanism comprising a plate cylinder adapted to carry single-page tubular plates and a pair of impression cylinders co-acting with said single plate cylinder at opposite points; with a second printing mechanism comprising an impression cylinder and two plate cylinders 110 each adapted to carry single-page tubular plates co-acting with said impression cylinder at opposite points, and means for directing pairs of webs successively between the single-plate cylinder and its co-acting 115 impression cylinders in one mechanism and between the single impression cylinder and its pair of co-acting plate cylinders in the other mechanism; with folding mechanisms adjacent each end of the press, and means for deflecting the printed webs laterally to 120 said folders.

125 5. In a rotary printing press, the combination of a series of printing mechanisms comprising plate and impression cylinders, 130

each plate cylinder being arranged between and coacting with two impression cylinders, and a second series of printing mechanisms comprising a plurality of impression cylinders and two plate cylinders co-acting with each impression cylinder, each plate cylinder being of small diameter and adapted to carry only single-page tubular plates extending around the circumference of the cylinders, and means for directing pairs of oppositely moving webs successively between a plate cylinder and impression cylinders in one series to be printed on one side and between an impression cylinder and plate cylinders in the other series to be perfected; with a plurality of folding mechanisms adjacent each end of the press, means for slitting the webs, and means for directing the halves of the similarly moving slit webs to the folding mechanisms.

6. In a rotary printing press, the combination of a series of printing mechanisms comprising plate-cylinders and impression cylinders, each plate cylinder being arranged between and co-acting with two impression cylinders and adapted to carry single-page tubular plates whereby two impressions may be taken simultaneously from each page-plate; and a second series of printing mechanisms comprising a plurality of impression cylinders and pairs of plate cylinders, each impression cylinder being arranged between and co-acting with two plate cylinders; with means for directing webs successively between a plate and impression cylinder in one series to be printed on one side, and then between an impression cylinder and plate-cylinder in the other series to be perfected.

7. In a rotary printing press, the combination of two adjacent series of printing mechanisms comprising alternate plate cylinders and impression cylinders, each plate cylinder being adapted to carry only single-page tubular plates; each plate cylinder in one series co-acting with two impression cylinders whereby two impressions are taken simultaneously from each single-page plate, and each impression cylinder in the other series co-acting with two plate cylinders; with means for directing a plurality of webs successively between printing couples in the adjacent series, folding mechanisms, and means for diverting the per-

fected webs from the press to such folding mechanisms.

8. In a rotary printing press, the combination of a series of printing mechanisms comprising plate and impression cylinders, each plate cylinder carrying only single-page tubular plates, and each plate cylinder being arranged between and co-acting with two impression cylinders whereby two impressions may be taken simultaneously from each single-page plate, and a second series of printing mechanisms comprising a plurality of impression cylinders and two single-page plate cylinders co-acting with each impression cylinder, and means for directing webs successively between the plate and impression cylinders in one series to be printed on one side and between the impression and plate cylinders in the other series to be perfected; with a plurality of folding mechanisms at the side and adjacent each end of the press, and means for giving the printed webs a quarter turn and directing them to said folding mechanisms.

9. In a rotary printing press, the combination of a series of printing mechanisms comprising plate and impression cylinders, each plate cylinder carrying only single-page tubular plates, and being arranged between and co-acting with two impression cylinders whereby two impressions can be simultaneously taken from each page-plate; and a second series of printing mechanisms comprising a plurality of impression cylinders and two plate cylinders co-acting with each impression cylinder; with means for directing pairs of webs in opposite directions successively between the plate and impression cylinders in one series to be printed on one side and between impression and plate cylinders in the other series to be perfected; a plurality of folding mechanisms adjacent each end of the press, means for slitting the webs, and means for directing the halves of the similarly moving slit webs to the same or separate folding mechanism.

In testimony that I claim the foregoing as my own, I affix my signature in presence of two witnesses.

HENRY F. BECHMAN.
